US00D735852S

(12) **United States Design Patent**
Minnelli et al.

(10) **Patent No.:** US D735,852 S
(45) **Date of Patent:** ** Aug. 4, 2015

(54) **FLUID REMOVER**

(75) Inventors: **Patrick J. Minnelli**, Harrison, OH (US);
Kevin M. Montgomery, Camden, OH (US)

(73) Assignee: **Ethicon Endo-Surgery, Inc.**, Cincinnati, OH (US)

(**) Term: **14 Years**

(21) Appl. No.: **29/428,238**

(22) Filed: **Jul. 27, 2012**

Related U.S. Application Data

(63) Continuation of application No. 12/902,265, filed on Oct. 12, 2010, now Pat. No. 8,636,686, which is a continuation-in-part of application No. 12/533,590, filed on Jul. 31, 2009, now Pat. No. 8,568,362, which is a continuation-in-part of application No. 12/110,724, filed on Apr. 28, 2008, now Pat. No. 8,579,807, and a continuation-in-part of application No. 12/110,727, filed on Apr. 28, 2008, now Pat. No. 8,870,747, and a continuation-in-part of application No. 12/110,742, filed on Apr. 28, 2008, and a continuation-in-part of application No. 12/110,755, filed on Apr. 28, 2008, now Pat. No. 8,273,060.
